UNITED STATES PATENT OFFICE.

WILLIAM A. KELSEY, OF MERIDEN, CONNECTICUT.

DESIGN FOR A PHOTOGRAPH-MOUNT.

SPECIFICATION forming part of Design No. 23,022, dated January 30, 1894.

Application filed October 10, 1893. Serial No. 487,777. Term of patent 7 years.

To all whom it may concern:

Be it known that I, WILLIAM A. KELSEY, of Meriden, Connecticut, have invented a new Design for Photograph-Mounts, of which the following is a specification.

In the accompanying drawing which is a plan view of my design the letter A designates the central portion or panel of a photograph card or mount, B designates the scalloped edge of the mount and C, a row of perforations near the edge B.

The leading features of my design are the central portion or panel, the scalloped border and the series of continuous marginal perforations within said border.

15

What I claim is—

The design for a photograph mount as herein shown and described.

WILLIAM A. KELSEY.
